CUSHION UNIT FOR UPHOLSTERY AND
METHOD OF MAKING THE SAMEFred A. Nachman, Jr., Chicago, Ill., assignor to
Nachman Springfilled Corporation, Chicago,
Ill., a corporation of Illinois

Application July 10, 1939, Serial No. 283,597

7 Claims.

(Cl. 5—351)

The invention relates to improvements in the upholstery art and particularly to the manufacture of spring assemblies for incorporation into mattresses and cushions and a method of producing the same at very small cost.

More particularly, the invention relates to what may be termed "jacketed spring assemblies" wherein an all-metal spring structure is enveloped in an upholstery batt and is secured thereto in such manner that the securing means serve several useful purposes as hereinafter fully described.

Several embodiments of the invention are illustrated in the accompanying drawings, wherein,

Fig. 1 is a vertical longitudinal sectional view, partly broken away, of a cushion unit constructed in accordance with the invention.

Fig. 2 is a vertical transverse sectional view of the same, also partly broken away, taken on the line 2—2 of Fig. 1.

Fig. 3 is a perspective view illustrating a modified form of the construction shown in Figs. 1 and 2 with parts broken away.

Fig. 4 is an end elevation of a strip of fibrous padding, such as a conventional type of sisal fibre batt constructed in accordance with the present invention.

Fig. 5 is a broken away perspective view of the structure shown in Figs. 6 and 7 illustrating the batt in its initial position on the spring assembly, the subsequent overlap of the ends of the batt, as shown at the right hand end of Fig. 6, being indicated in dotted lines.

Fig. 6 is a vertical longitudinal sectional view of the same on an enlarged scale, partly broken away, on the line 6—6 of Fig. 7.

Fig. 7 is a fragmentary vertical transverse sectional view of the structure shown in Figs. 5 and 6 on the same scale as Fig. 6.

Fig. 8 is a fragmentary plan view of the batt element of the structure of Figs. 5—7 inclusive.

Fig. 9 is a transverse sectional view of the same on the line 9—9 of Fig. 8.

Fig. 10 is a view similar to Fig. 2 on a smaller scale showing another embodiment of the invention.

As shown in Fig. 4, a fibre batt or pad 1, of any of the conventional types commonly used in upholstery, and which may be composed of stitched sisal fibre of a conventional type, is equipped along its side edge portions with strips 2 of fabric secured thereto by stitch chains 3 spaced from the side edges of the batt and disposed between the side edges of said strips 2.

The said stitch chains 3 along opposite edge 55

portions of the batt 1 are spaced from each other substantially a distance equal to or slightly less than the width of the spring assembly to be enveloped by the batt and are spaced, preferably, equidistantly from the side edges of the batt for a substantial distance.

A batt of the type shown in Fig. 4 is made of somewhat greater width than the spring assembly 4 and is preferably of sufficient length to completely envelope said spring assembly, which may be of any conventional type, an exemplary type being shown in Fig. 1. Said spring assembly may be equipped with or devoid of border wires or other marginal frame elements also common in the art.

In the instance of Fig. 1, the length of the batt or pad is such that its ends meet at the point 5.

The width of the batt, as above stated, is somewhat greater than the width or length of the spring assembly to be enveloped thereby, depending upon whether the batt is disposed to extend transversely about an assembly for a mattress or cushion or longitudinally thereof, but in the case of a spring assembly for seat cushions, the batt will be so disposed about the said assembly as to have the side edges of the batt extend along the longitudinal edges of the spring assembly with the vertically disposed portions of the batt at front and rear of the spring assembly.

The said batt 1 is lapped about the spring assembly so that the fabric strips 2 are disposed upon the outer face of the same.

After the batt 1 has been so disposed about the spring assembly, as shown in Fig. 1, the outwardly projecting portions or flaps of the strips 2 are drawn downwardly from the upper edges of the horizontal face of the batt and upwardly from the lower face of the batt so that their edges meet and said meeting edges are then secured together along a horizontal plane substantially midway between the upper and lower faces of the spring assembly by means of stitch chains 6. The last-named flaps or flanges are drawn together with sufficient force to cause the side edge portions of the batt covering the top and bottom faces of the spring assembly to be drawn down over the edges of the spring assembly which they cover substantially as shown in Fig. 2, thereby firmly securing the batt to the spring assembly.

Thus if the stitch chains 3 are spaced apart a distance equal to the width of the spring assembly or slightly less, the tautness of the portions joined by the stitch chains 6 will stretch the batt tautly over the faces of the assembly

and will cause the stitch chains 3 to become aligned substantially with the planes of the upper and lower faces of said assembly and will crowd the portions of the batts pierced by said stitch chains 3 and normally compressed by them, to hug the side edges of the assembly very closely and will also cause the outermost adjacent free side edge portions of the batt to turn inwardly to underlie the side edge portions of the top and bottom faces of said assembly. As these side edges are relatively sharp, or rough, the batt thus becomes so firmly secured against displacement as to obviate the use of further securing means.

The strips 2 extend the entire length of the batt 1 and become folded transversely at their middle portions, the stitch chains 6 extending substantially the entire length of said strips. The meeting edges 5 of the batt may be stitched together by means of loop stitches 7 if desired and thus the spring assembly becomes completely housed by said batt and the last-named portions of the strips 2.

After the said strips 2 have been secured together by the stitch chains 6, an endless band 8 of resilient foamed latex compound is disposed about the spring assembly and the batt enveloping the same with the side edges of said band disposed flush or substantially flush with the outermost edges of the side edge portions of the batt aligned with the stitch chains 6. The other or inwardly extending portions of the strips 2 are then cemented to the opposed side edges of the band 8 to secure the latter firmly in place. The band 8 is stretched slightly to receive the batt-enveloped spring assembly 4 and is thus rendered self-retained in place and acts also to secure the batt more firmly against displacement relatively to the spring assembly 4.

As shown in Fig. 3, instead of using an endless band 8 of said foamed latex, pads 9 of the same material, equal in width and length to the batt enveloped spring assembly, may be disposed upon the upper and lower faces of the batt and secured in place by means of the said last-named upwardly and downwardly extending portions of the strips 2 and, if desired, strips 10 of fabric may be cemented to the front and rear edges of said pads to cover the front and rear face portions of the foamed latex pads 9 to further secure the same to the spring assembly.

Obviously, if desired, only one of said pads 9 may be employed to cover the upper face of the structure, leaving the lower face free of any covering except the ultimate outer cover fabric common to all cushions and mattresses.

In instances (as exemplified in Figs. 5 to 9) where the spring assembly is sold devoid of the foamed latex or other additional layers of padding, it is preferred to secure strips 2a of a suitable fabric to the outer faces of the side edge portions of the parts of the batt 11 overlying the top and bottom faces of the batt 11, by means of stitch chains 12, the said batt 11 being of such length as to not only completely envelope the spring assembly, but also to cause the end portions 13 of the batt to be overlapped, as shown in Fig. 6, said overlapped edge portions being stitched together by means of stitching 14.

In this instance the batt 11 will also be of greater width than the spring assembly enveloped thereby and after said batt has been disposed about the spring assembly, as shown in Fig. 7, the portions 2a of the fabric strips stitched to the batt along its side edge portions are turned

downwardly from the upper portion and upwardly from the lower portion of the batt into position to be joined by means of stitch chains 18 identical with the stitch chains 6 of Figs. 1 and 3, the spring assembly being (as in the case of Figs. 1-3 inclusive) of any of the various conventional types. Thus the outer edge portions of the batt 11 become reversed in position and the side edge portions of the batt 1 are not only drawn downwardly to cover the corresponding peripheral edges of the spring assembly, but also inwardly to cover the lower faces of the peripheral edge portions of the top and bottom parts of the spring assembly, the joined and tensioned flaps 2a being then disposed in vertical planes substantially aligned vertically with the outermost peripheral portions of the spring assembly which is generally and most commonly equipped with a suitable border wire 19 along its top and bottom edges as shown in Fig. 7.

Obviously, the strips 2 or 2a when stitched together by stitch chains 6 and 18, respectively, serve not only to maintain the top and bottom portions of the batt in place on the spring assembly against lateral movement, but also serve to hold said respective batts against longitudinal movement relatively to or about the spring assembly. In each instance the peripheral edges of the batt along the top and bottom faces of the spring assembly are nicely rounded and particularly so in the instances of Figs. 5-9 inclusive. This is advantageous in inserting the spring assemblies into the cover fabrics of the mattresses and cushions, said batts being further advantageous in that they thoroughly pad the border wire frames of the spring assembly.

In the structures wherein the resilient molded pads are included, the strips of fabric secured to the batts and stitched together along the sides 40 of the structure, constitute continuous webs which not only secure the batt or batts to the spring assembly, but also secure the pads to the batt or batts, and also secure the pads to each other. Hence, any stress along a side of a top 45 or bottom pad or pad portion, tending to displace it, will be transmitted to the opposite pad as well as to the batt and by the latter to the corners along the top and bottom of the spring assembly in line with the direction of stress. The 50 batt obtains a strong frictional hold on the assembly along the top and bottom corners of the latter so that displacement of any part of the structure relatively to any other part thereof is substantially impossible.

Thus, as exemplified in Fig. 10, each of the webs 2a may be of such width as to include portions 20 or 21, one of which is disposed to completely cover the batt 1 which it borders and be secured by stitching 22 along its outer or normally free edge to the extension portion 21 of the other web 2a adjacent the stitch chain 3 which secures the latter to said batt. The last-named extension portion 21 may be of even greater length and disposed to overlie the top and sides of the resilient pad 9 and be secured along its initially free edge portion to the other web 2a by stitching 23 adjacent the stitch chain 3 which secures the latter to said batt.

Additionally, the extension portion 21 may be provided with hems 24 so disposed as to be located at the corners of the resilient pad 9 and to which the meeting edges of the boxing strip and cover fabric of the casing of the ultimate mattress or cushion may be secured in a well known manner.

Obviously, the free edge portions of the upwardly and downwardly projecting portions of the strips 2 and 2a cemented to peripheral faces of the resilient pad, provide flanges 25 to which the meeting edges of the boxing strip and cover fabrics of the ultimate mattress or cushion may be secured in said well known manner, reference being had to Patents Nos. 2,069,415 and 2,129,038.

In the structure of Fig. 10, the right hand end of the portion 20 may be secured in the position shown simultaneously with the stitching of the right hand strip 2a to batt 1 by means of the stitch chain 3 and in that event the stitching 22 may be omitted.

In all instances wherein the marginal springs of the spring assembly are longer than the other springs thereof, and are connected with the next adjacent inner springs, which is common in the art, the periphery of the assembly is of greater height than the middle portion thereof. In such instances the webs 2 and 2a, respectively, are drawn so taut as to reduce the height of the periphery of the assembly to that of the middle portion of the same.

The batts used may be of any type composed of long fibre, such as sisal, wherein the fibres are held against relative displacement by stitching and which may be devoid of or equipped with a backing sheet of fabric through which the said passes, or the same may be of the quilted type wherein the fibrous constituent is disposed between fabric sheets. All of these types of batts as so well known to those skilled in the art that illustrated and particular description thereof is deemed to be unnecessary.

Obviously in instances where the batt is equipped with fabric sheet backing or is quilted, as aforesaid, the stitch chains 3 will be passed through the fabric also.

The width of the portions of the fabric strips 2 which are shown and described as cemented to the latex pad may be appreciably greater than shown with outermost portions overlying or otherwise arranged relatively to said latex pad, but in such manner as to secure the latter in place.

I claim as my invention:

1. A cushion unit for upholstery comprising a conventional spring assembly, a continuous batt structure of greater width than said assembly disposed about the same with its side edge portions embracing the peripheral edges of the top and bottom portions of the latter, fabric strips secured between their side edges to side edge portions of the said batt and presenting oppositely extending flaps along the sides of said assembly, opposed portions of said flaps being secured together in a plane substantially midway between the top and bottom portions of said assembly and providing side closures for the latter, corresponding other portions of said flaps extending outwardly from a load-supporting face of the batt-enveloped assembly along the side edges thereof, and a resilient unitary pad of foamed latex or the like disposed between and secured to said last-named flaps.

2. A cushion unit for upholstery comprising a spring assembly, fibre batt coverings of greater width than said assembly overlying the top and bottom faces of the latter, fabric webs secured to the side edge portions of the batt coverings and connecting the same and overlying the sides of the assembly and spaced outwardly from the same, free extension portions of said webs ex-

tending upwardly from said webs in the vertical planes of the said webs, and a unitary resilient pad of foamed latex or the like disposed over the last-named face of said batt covered assembly and having side faces disposed in the planes of said webs and secured to said free portions of the latter.

3. A cushion unit comprising a spring assembly, batt coverings of greater width than the top and bottom faces thereof completely covering the latter, fabric strips secured to the outer faces of said coverings along side edge portions thereof by means of stitch chains disposed initially in substantial alignment with the vertical planes of the side edges of the assembly and disposed in spaced relation to the side edges of said fabric strips and spaced from the side edges of said coverings, the outer edge portions of the said strips at top and bottom of the structure being drawn toward each other and secured together to oppose and close the sides of said assembly and cause said stitch chains to become disposed substantially in the planes of the top and bottom faces of the assembly with the free edge side portions of said coverings projecting inwardly of the side edges of said assembly, the other edge portions of said strips constituting initially free flaps and a unitary resilient pad of foamed latex or the like disposed over the last-named face of said batt-covered assembly and having side faces disposed in the planes of said webs and secured to said free flaps.

4. An upholstery unit comprising a spring assembly, batt elements covering both faces thereof and having their side-edge portions disposed in embracing relation to the side-edge portions of the upper and lower faces of the assembly, a web of fabric secured along opposite side edge portions to the opposed edge portions of said batt elements by means of stitch-chains spaced from the side edges of said batt elements and from the side edge portions of said webs, the portions of the latter disposed between the said stitch-chains being of less depth than the normal depth of the space between the portions of said batt elements connected with said webs by the latter whereby said webs are maintained taut and the side edge portions of said batt elements are maintained in their said embracing relation to the side edge portions of said assembly, the outer edge portions of said webs projecting outwardly from the said stitch-chains.

5. An upholstery unit comprising a spring assembly having batt covered upper and lower faces, the cover batts of said faces being of greater width than the latter with their side edge portions constituting flanges, turned inwardly into embracing relation to the upper and lower side edges of the spring assembly, a pair of fabric webs secured along their upper and lower edge portions to said flanges by means of stitch-chains spaced from the said edges of said webs and from the inner edges of said flanges and spaced apart a distance less than the depth of space between the opposed inturned edges of said flanges, the edge portions of said webs constituting flanges, and a pad element disposed over one of said cover batts and secured along its side edges to the last-named flanges, said webs acting to maintain the side springs of the assembly partly compressed and to maintain the said cover-batts taut and the side flanges thereof in said embracing relation to the side edges of the assembly.

6. A structure of the type specified comprising

a conventional spring assembly, batt coverings of greater area than the faces of said assembly disposed over the upper and lower faces of the latter and each presenting opposed peripheral edge portions folded about and in embracing relation to corresponding peripheral edge portions of the upper and lower faces of said assembly, with free edge portions thereof turned inwardly, and in embracing relation thereto, and a pair of substantially taut fabric webs secured along upper and lower side edge portions to the said inwardly turned edge portions by rows of fastening means spaced from the free edges of said coverings, said webs disposed substantially in the planes of the embraced edges of said assembly and constituting means whereby the batt coverings are maintained in place.

7. The herein-described method of making a pad-covered spring assembly which consists in first providing batt coverings of greater width than the spring assembly, then securing to each of the side edge portions of each of said batt coverings upon their outer faces a strip of fabric by means of stitch chains spaced apart a dis-

tance substantially equal to or slightly less than the width of said assembly and extending through said coverings, then disposing said coverings over the faces of said assembly, then turning said fabric strips over the side edge portions of said coverings to thereby cause the free side edge portions of the latter to overhang the side edges of the upper and lower faces of the assembly and thereafter, while the side edge portions of said assembly are maintained free, securing the edge portions of the fabric strips of the upper covering to the opposed free edge portions of the fabric strips of the lower covering in such manner as to form composite webs of widths less than the normal distance between the first-named stitch chains at each side of the assembly, and then allowing the side edge portions of the latter to expand and thereby tensioning the webs and the coverings and causing the free edge portions of said coverings to embrace the edges of the assembly and said webs to become disposed in the planes of the edges of the assembly so enveloped.

FRED A. NACHMAN, JR.
